UNITED STATES PATENT OFFICE.

JOHN JAMES KEARNEY, OF BALTIMORE, MARYLAND.

CHUCK AND BORING-TOOL.

SPECIFICATION forming part of Letters Patent No. 727,639, dated May 12, 1903.

Application filed February 5, 1902. Serial No. 92,628. (No model.)

To all whom it may concern:

Be it known that I, JOHN JAMES KEARNEY, a citizen of the United States, residing at Baltimore, in the State of Maryland, have invented certain new and useful Improvements 5 in Chucks and Boring-Tools, of which the following is a specification.

The purpose of this invention is to provide a chuck and a tool-shank provided with parts 10 which interlock with the jaws of said chuck, whereby the shank of the tool may be positively turned by the jaws, whether loosely engaged or tightly gripped by the jaws, and means for locking the tool-shank against 15 withdrawal from the chuck when loosely engaged by the jaws. By means of these improvements reamers, in the use of which it is desirable to allow slight lateral play, may be held within the chuck against longitudinal 20 movement while loosely engaged by the jaws, and boring-drills may be gripped firmly by the jaws in the usual manner. The arrangement is such that tools of various sizes and having shanks of the same general design 25 may be held within the chuck.

In the accompanying drawings, which illustrate the invention, Figure 1 is a longitudinal section through the chuck, taken on the line between the jaws, a part of the chuck-spindle 30 being shown in side view. Fig. 2 is a section on the line A A of Fig. 1, the spring-pawl being removed. Fig. 3 is a central sectional view through the chuck, showing a reamer held therein and having the spring-pawl connected to the head in a different manner from that shown in Fig. 1. Fig. 4 is an end view of the chuck, the reamer being shown in section on the line B B of Fig. 3. Fig. 5 is a perspective view showing a tool of small diameter held within a detachable shank. Fig. 6 is a front end view of the shank shown in Fig. 5, the drill being shown in cross-section. Fig. 7 is a perspective view showing the shank of a drill of larger diameter. Figs. 8 and 9 are end views of the shank of tools having different diameters. Fig. 10 is an end view of a chuck, the opposing jaws of which flare outwardly from the center; and Fig. 11 is an

end view of the shank of a tool adapted to fit the chuck shown in Fig. 10. 50

Referring to Figs. 1 to 4, inclusive, of the drawings, the chuck comprises a cylindrical head *a* upon a shank or spindle *1*, said head being divided into two opposing jaws *2* and *3* by a slot passing diametrically through the 55 head and extending from its outer end to the base *4*. The head is bored axially inward from the outer end, forming central guide-grooves *5* and *6* in the faces of the jaws, and suitable stops *7* for the shank of the tool are 60 provided at the bases of the grooves. A sleeve *8* is threaded onto the jaws and the outer end 9 of the sleeve is conical and adapted to bear against the tapering ends *10* of the jaws for the purpose of forcing the latter inwardly 65 against a tool-shank.

The tool-shanks in cross-section conform to the shape of the grooved slot between the jaws, each shank, as clearly shown in Figs. 4 to 9, inclusive, having a central portion *11*, 70 the sides *12* of which are arcuate in form and adapted to fit within the grooves *5* and *6*, and projecting laterally in opposite directions from the central portion are ribs or wings *13*, adapted to enter between the flat faces *14* of 75 the jaws.

It will be seen that when a tool-shank is placed within the chuck the part *11*, fitting within the grooves *5* and *6*, centers the tool, while the faces *14* engage the wings *13* and 80 turn the tool positively. When a boring-tool such as that shown in Fig. 7 is to be used, the sleeve *8* is screwed inward upon the chuck-head, and the jaws are thereby clamped tightly upon the shank of the tool. In using 85 reamers, however, it is desirable to permit the reamer to adjust itself to the opening in which it is operating, and for this reason provision is made for holding the shank of a reamer loosely within the chuck. 90

In Fig. 3, *15* indicates a reamer-shank having the form above described and having notches *16* in the wings *13*, which are engaged by pawls or catches *17* upon springs *18*, which springs, as shown in Fig. 3, are secured to 95 the head at the base of the slot by screws *19*,

and extend outwardly between and beyond the jaws, terminating in outwardly curved ends 20. In Fig. 1 the springs are secured to the head by having their inner ends 21 bent toward each other and fitting within notches formed in the head. When the reamer-shank is placed within the chuck, the pawls 17 spring into the notches 16, and thereby lock the tool against withdrawal from the chuck. It is then unnecessary to clamp the jaws against the tool-shank for the reason that the tool cannot fall or be pulled out of the chuck without releasing the pawls, and the tool-shank will be positively driven by the engagement of the faces 14 with the ribs or wings upon the shank. As shown in Fig. 3, the sleeve 8 is not screwed inwardly, so as to bind against the jaws when the reamer is in use, and therefore the shank of the reamer fits loosely between the jaws, as illustrated in Fig. 4. The reamer may be readily removed at any time by simply spreading the outer ends 20 of the spring-pawls with the fingers, thereby disengaging the pawls from the notches in the shank.

The boring-tools, as shown in Fig. 7, are not provided with notches, as it is desirable to clamp such tools firmly within the jaws, and it is unnecessary to provide other retaining devices. The diameter of the central part 11 of each tool-shank is the same, but the depth of the ribs depends upon the diameter of the tool, as will be seen from an inspection of Figs. 8 and 9, which represent end views of drills of different sizes.

In order to hold drills of small diameter within the chuck, a detachable shank *b* is provided, as shown in Figs. 5 and 6, said shank consisting of a part having the same general cross-section as the shanks of the larger tools and having a slot 22 extending inwardly from one end and centrally through the shank in the line of the ribs, thus dividing the said part into two similar spring-jaws 23, which are united at one end. The part has an axial bore forming grooves 24, adapted to receive a small boring-tool 25. Notches 26 are formed in the ribs of the detachable shank and adapted to be engaged by the spring-pawls of the chuck. It will be seen that when the detachable shank is inserted within the chuck and the sleeve 8 screwed inward to clamp the jaws of the chuck upon the jaws of the detachable shank the drill will be firmly held in place. Owing to the engagement of the spring-pawls with the notches in the detachable shank it will be apparent that when the jaws of the chuck are released the drill may be removed without removing the shank, and a new drill may be inserted.

In Fig. 10 the faces 14^a of the chuck-jaws are flared outwardly from the grooves instead of being parallel, as shown in the other figures of the drawings. This construction for

some reasons is preferable to the parallel arrangement of the jaws. The tool-shanks adapted for jaws of this form are provided with wings or ribs 13^a, which, as shown in Fig. 11, are wedge-shaped in cross-section and adapted to fit between the flaring faces of the chuck-jaws. This construction permits the wings to be made stronger by reason of the greater quantity of metal toward the outer ends of the wings.

Having described my invention, what I claim, and desire to secure by Letters Patent, is—

1. The combination with a chuck having movable jaws and a tool-shank having laterally-projecting wings or ribs constructed to interlock with and be turned by said jaws while loosely held therein, of means for retaining the shank within the chuck while fitting loosely within the jaws.

2. The combination with a chuck comprising a pair of separated jaws having central longitudinal grooves in their opposing faces, and pawls arranged between said jaws, of a tool provided with a shank having a central portion adapted to fit within said grooves and laterally-projecting wings adapted to be engaged loosely by the jaw-faces at either side of the grooves, said wings having notches therein adapted to be engaged by the pawls.

3. A chuck having jaws constructed to loosely interlock with parts of a tool-shank whereby the tool may be turned by the chuck, and one or more spring-pawls or catches secured within the chuck and extending outwardly beyond the end of the chuck.

4. A chuck having a pair of jaws provided with longitudinal grooves on their opposing faces, and one or more spring-pawls or catches secured to the chuck and extending outwardly between said opposing faces beyond the end of the chuck.

5. The combination with a chuck having jaws and a clamping-sleeve therefor and a tool having a shank provided with parts adapted to interlock with the chuck-jaws, of one or more spring-pawls secured within the chuck and extending outwardly beyond the end of the sleeve and adapted to engage and lock the shank against withdrawal from the chuck.

6. The combination with a chuck and a tool-shank having laterally-projecting wings or ribs adapted to interlock loosely with the chuck and notches in said wings, of spring-pawls arranged to engage said notches.

7. The combination with a chuck having jaws and means for compressing the jaws of a removable tool-shank having wings adapted to interlock with said jaws, said shank being longitudinally slotted and having a groove adapted to receive a tool, of means for retaining said shank within the chuck-jaws when the latter are relaxed.

8. The combination with a chuck comprising a pair of movable jaws having central

longitudinal grooves in their opposing faces, the faces of said jaws flaring outwardly from the grooves, of a tool having a shank provided with a central portion adapted to fit within 5 said grooves and laterally-projecting wedge-shaped wings adapted to be engaged loosely by the flaring faces of the jaws, said wings having notches therein, and spring-pawl

within the chuck adapted to engage with said notches.

In testimony whereof I affix my signature in presence of two witnesses.

JOHN JAMES KEARNEY.
